UNITED STATES PATENT OFFICE

114,066

DESIGN FOR A GAME BOARD

Floyd P. Hazelwood, William N. Sherman, and
Elmer C. Wheeler, Topeka, Kans.

Application January 27, 1939, Serial No. 82,640

Term of patent 3½ years

To all whom it may concern:

Be it known that we, Floyd P. Hazelwood, William N. Sherman, and Elmer C. Wheeler, citizens of the United States of America, residing at Topeka, in the county of Shawnee and State of Kansas, have invented a new, original, and ornamental Design for a Game Board, of which the following is a specification, reference being had to the accompanying drawing, forming part thereof.

Figure 1 is a top plan view of a game board showing our new design; and

Figure 2 is a sectional view taken on line 2—2 of Figure 1.

We claim:

The ornamental design for a game board, as shown.

WILLIAM N. SHERMAN.
FLOYD P. HAZELWOOD.
ELMER C. WHEELER.
